(57) **CLAIM**

I claim the ornamental design for a floor cleaning implement, as shown and described.

DESCRIPTION

FIG. 1 is a top, front, and left perspective view of a floor cleaning implement according to the design;

FIG. 2 is a left elevational view thereof;

FIG. 3 is a right elevational view thereof;

FIG. 4 is a rear elevational view thereof;

FIG. 5 is a front elevational view thereof;

FIG. 6 is a top plan view thereof;

FIG. 7 is a bottom plan view thereof;

FIG. 8 is a cross-sectional side view thereof taken through line 8-8 of FIG. 6; and,

FIG. 9 is a cross-sectional side view thereof taken through line 9-9 of FIG. 6.

The broken lines shown in the drawings are for the purpose of illustrating unclaimed portions of the floor cleaning implement, and form no part of the claimed design.

In a preferred embodiment, the nature of this product is as a floor cleaning implement, such as a disc brush, for a floor maintenance machine.
